FLUID CONTROL DEVICE

Howard F. Lawrence, Philadelphia, Pa., assignor
to American Engineering Company, Philadelphia, Pa., a corporation of Pennsylvania

Application October 31, 1936, Serial No. 108,599

9 Claims. (Cl. 110—44)

This invention relates to fluid control devices, and more particularly to fluid control devices associated with the tuyères of a furnace stoker.

One object of the present invention is to provide a generally improved fluid control device which is automatic in operation, and which may be readily attached to the tuyères of a stoker.

A more specific object is to provide a fluid control device of a unitary construction comprising a substantially box-like casing adapted for attachment to the end of a tuyère, and a damper element pivotally mounted in said casing.

Another object is to provide improved pivotal mountings for the dampers of fluid control devices which are not subject to binding due to corrosion, dust accumulations, or to the expansion and contraction of the parts, whereby proper operation, as well as longevity of service of the fluid control devices is assured under all conditions of operation.

Other and further objects will become apparent as the description of the invention progresses.

Of the drawings:

Fig. 1 is a longitudinal sectional view taken through one of the retorts of an inclined grate, multiple retort stoker of the underfeed type.

Fig. 2 is an enlarged sectional view taken through the upper end of one of the tuyère rows showing an improved fluid control device attached to each of the tuyères thereof.

Fig. 3 is a plan view of a tuyère block showing a pair of fluid control devices attached thereto.

Fig. 4 is an end view taken substantially along line 4—4 of Fig. 3, showing the fluid control devices attached to a series of tuyère blocks.

Fig. 5 is a perspective view of one of the fluid control devices comprising the present invention.

Fig. 6 is a perspective view of the fluid control device shown in inverted position.

Fig. 7 is a plan view of a tuyère block of a slightly modified construction having a single fluid control device attached thereto, and

Fig. 8 is an end view taken substantially along line 8—8 of Fig. 7, showing fluid control devices provided on a series of tuyère blocks.

Referring to the drawings, the numeral 1 indicates generally a stoker of the inclined grate, multiple retort, underfeed type, to which, for the purpose of illustration, the fluid control devices comprising the present invention, are applied. Stoker 1 is of usual construction and comprises a series of alternately disposed retorts 2 and tuyère rows 3. Fuel is supplied to the retorts 2 from a hopper H disposed exteriorly of the front

wall 4 of the furnace, and which communicates with a series of cylinders 5 having rams 6 operating therein, driven by any suitable power mechanism 7. Thus, upon reciprocation of the rams 6 predetermined quantities of fuel are fed to the stoker. A series of pushers 8 is provided in the bottom of each retort 2 which underfeed the fuel therealong to extension grates 10 disposed at the lower end of the stoker. The pushers 8 are also actuated by the power mechanism 7 through any suitable link and lever mechanism indicated generally by the numeral 11. Draft air is supplied to the tuyères 3 from a plenum chamber 12 disposed beneath the stoker, and which in turn is supplied with draft air by any suitable fan or blower mechanism (not shown) through a passage 13.

Each of the tuyère rows 3 comprises a series of tuyère blocks 14 arranged in superimposed stepped relation over the length thereof, each tuyère block consisting of a relatively flat body portion 15, having a forwardly disposed, substantially rectangular air inlet end 16, and a substantially rounded air discharge end 17. Depending from the under side of the body portion 15 adjacent the side edges thereof are a pair of supporting members 18, 18 which in assembly rest upon the side plates 19, 19 of adjacent retorts in a well known manner. Disposed between supporting members 18, 18 and extending longitudinally of the tuyère block from the forward end thereof are a pair of depending ribs 20 and 21. These ribs terminate at their rearwardly disposed ends in an enlarged rib 22 having a substantially rectangular aperture 23 provided therein. A hook 24 depends from rib 22, and in assembly extends into the aperture 23 of the next lower tuyère block of the series, as shown in Fig. 2, to retain the tuyère blocks in position. Extending to substantially the discharge end of the tuyère block 15 from the rearwardly disposed edge 25 of rib 22 is a relatively narrow rib 26 which, with rib 23 and ribs 20 and 21, divide the tuyère block in halves. The rearwardly disposed edges 27 and 28 of supporting members 18, 18 incline outwardly toward the side edges of the tuyère block, while the side edges 29 and 30 of rib 22 opposite thereto converge toward rib 26, thereby forming a pair of discharge passages 31 and 32 having restricted throats and diverging side walls. Disposed between edges 27 and 29, and between edges 28 and 30 are a series of ribs 33 which are arranged substantially fan-like in passages 31 and 32, and which define a series of passages 34 having restricted inlet ends 35 and 36.

diverging side walls. The forwardly disposed ends of ribs 33 are substantially arcuate, whereby the throat of the passages 34 are of substantially Venturi construction. The inner forwardly disposed faces 36 and 37 of supporting members 18, 18 form with ribs 20 and 21 respectively, a pair of inlet passages 38 and 39, which communicates with passages 31 and 32.

In the embodiment of the invention shown in Figs. 3 and 4, a fluid control device 40 is provided for and neatly occupies each of the passages 38 and 39. Each air control device 40, as shown more particularly in Figs. 5 and 6, comprises a casing 41 of substantially box-like construction, having a flat upper wall 42 and vertically disposed side walls 43 and 44. Secured to top wall 42 and extending between side walls 43 and 44 near the forwardly disposed ends thereof is a hook 45, which in assembly is adapted to engage the forwardly disposed end of a tuyère block 14.

The bottom of casing 41 is open, as shown in Fig. 6, except that the rearwardly disposed end thereof is provided with a cross sealing strip 46, secured to and extending between side walls 43 and 44, and which, in assembly, rests upon the upper, forwardly disposed end of the next lower tuyère block 14 of the series, as shown in Fig. 2. Mounted on a pair of straps 47 and 48 is a damper element 49. This damper is of the general type shown and described in the pending application of William V. Sauter, and Howard F. Lawrence, Serial No. 22,217, filed on May 18, 1935, and comprises a relatively flat, longitudinally extending portion 50 terminating at the rearwardly disposed end thereof in a substantially arcuate portion 51 which lies in substantially abutting relation with the inner edge 52 of cross strip 46. Portions 50 and 51 extend between side walls 43 and 44, sufficient clearance being provided to permit vertical movement thereof. When the damper 49 is in fully open position the portion 50 thereof rests upon a pair of supporting lugs 54 and 55 extending inwardly from the lower edges of side walls 43 and 44, as shown in Figs. 2 and 5. The straps 47 and 48 may be constructed of any suitable material, such as of cords or strips of metal, or of non-inflammable compositions, as desired, and are secured at one end to damper 49 in any suitable manner, such as by rivets 56. The other ends of straps 47 and 48 are adjustably secured to a cross strip 57 by means of a clamp bar 58. Cross strip 57 is secured to and extends between the side walls 43 and 44 of casing 41 and the clamp bar 58 is secured thereto by any suitable means, such as by screws 59. Damper 49 may thus be adjusted longitudinally until the arcuate portion 51 thereof lies in substantially abutting relation with the inner edge of cross strip 46. The screws 59 are then tightened and the damper is securely held in adjusted position. It therefore is apparent that when damper 49 is adjusted as just described, into substantially abutting relation with cross sealing strip 46, but little leakage occurs around the end of the damper.

The casing 41, as well as the damper 49 of the fluid control devices 40, are preferably constructed from sheet metal. As shown in Figs. 5 and 6, the top and side walls, as well as hook 43 and supporting lugs 54 and 55 of the casing 41, may be formed from a single sheet of material. Cross strips 46 and 57 may then be readily secured thereto by rivets, spot welding, or by any other suitable means. Damper 49 obviously may also

be formed from a single sheet of material, and may be readily assembled in the casing 41.

From the foregoing description, it is seen that to assemble the fluid control devices 40 upon the tuyère blocks it is only necessary to insert the hooks 45 thereof over the forwardly disposed ends of the tuyères whereupon the devices will assume the position shown in Figs. 2, 3 and 4. Normally the dampers 49 will rest upon the supporting lugs 54 and 55, whereby the rearwardly disposed face 10 of arcuate portion 51 thereof will lie forwardly of the ends of tuyère blocks 14. Thus a passage is defined by the walls 42, 43 and 44 of casing 41 and the top of damper 49, which communicates with the inlet passages 38 or 39 of the tuyère block proper. Thus, the upper surface of each damper 49 is subjected to the pressure of the fluid flowing through the associated passage of the tuyère block, while the lower surface thereof, as will be seen upon reference to Fig. 2, is 20 at all times subjected to the pressure of the fluid in plenum chamber 12. It therefore is apparent that when fluid from chamber 12 flows through the tuyère blocks, the dampers associated therewith are subjected to differential pressures, the 25 pressure at the upper surfaces thereof being always less than that applied to their lower surfaces. The dampers 49 are so designed that the dead weights thereof will hold them open so long as the fuel bed overlying the associated tuyère 30 blocks remains at a normal density. However, should a thin spot occur in the fuel bed, thereby reducing the resistance to the flow of air through the tuyère block or tuyère blocks underlying the same, the velocity of the air passing through the 35 latter increases, and as a result the associated dampers are subjected to differential pressures greater than normal. When these differential pressures are sufficient to overcome the weight of the dampers the latter will move upwardly to sub- 40 stantially closed position, thereby shutting off the air flow to the associated tuyère blocks. The combustion rate at such thin portions is thus reduced and they may be built up by the fuel feeding elements to a normal condition again. 45 When such portions again approach a normal condition, thereby imposing a greater resistance to the flow of air through the associated tuyère blocks the differential pressure acting on the associated dampers decreases, and consequently the 50 dampers will move by gravity to open position.

By the construction shown in Figs. 3 and 4, it is seen that the flow of air to both sides of the tuyère blocks is effectively controlled, since in certain cases the density of the fuel overlying one 55 side of the tuyère may be greater than that overlying the other side thereof. Under such conditions the damper associated with the side of the tuyère having the greatest density will remain open, while that associated with the opposite side 60 will close until the fuel bed overlying the same approaches a normal density.

Figs. 7 and 8 show an alternative construction wherein but a single air control device 40' is provided for each of the tuyère blocks 14'. Tuyère 65 block 14' is similar in construction to tuyère block 14 except that the intermediate ribs 20 and 21 have been eliminated therefrom, whereby the rearwardly disposed end 16' between supporting members 18', 18' is relatively smooth at both 70 the upper and lower surfaces thereof. The fluid control devices 40' are identical in construction to the control devices 40 except that they are constructed to extend substantially the entire distance between the inner edges 36' and 37' of 75

supporting members 18', 18'. This construction affords a single damper element 49' which functions to control the draft air to both sides of the tuyère block.

5 From the foregoing description it is seen that a highly useful, as well as effective fluid control device has been provided, which is of a unitary construction and may be readily installed on stokers already operating in the field. The control device being constructed to fit tuyère blocks of standard construction, eliminates the necessity of providing special mountings when it is desired to install air control devices thereon. It is also seen that by providing straps 47 and 48 10 to pivotally support the dampers the severe conditions under which they operate do not affect the efficiency thereof, since the pivotal mountings are such that any corrosion thereof due to moisture and dust accumulations, do not affect their operation, and as a result the control devices are 15 adapted to operate for long periods of time without requiring attention. However, in the event it should be desired to install new control devices the old ones may be removed and new ones readily substituted therefor without interfering with the adjacent devices.

20 The specific type of damper employed herein is simply shown for the purpose of illustration, and it is not intended to limit the invention thereto since other forms of dampers may obviously be employed without departing from the invention. It therefore is to be understood that the invention is to be limited only to the scope of the claims which follow.

25 35 What is claimed is:

1. In a device of the class described, the combination of a tuyère block adapted to receive fluid from a source of supply, means provided on said tuyère block defining an inlet passage for fluid, a 30 fluid control device detachably secured to said fluid emitting device, said fluid control device comprising a substantially box-like casing communicating with said inlet passage, a damper element pivotally mounted in said casing, one side 40 of said damper element being subjected to the pressure of the fluid in said casing and the other side thereof being subjected to the pressure of the fluid at said source of supply, whereby, when said differential pressure exceeds a predetermined 45 value, said damper element moves to closed position, and one or more longitudinally adjustable straps for pivotally attaching said damper element to said casing.

50 2. A fluid control device comprising, a substantially rectangular casing, said casing having top and side walls, a sealing member extending between said side walls in spaced relation to said top wall, a hook secured to said top wall adapting said casing for attachment to a tuyère block, a 55 cross member secured to said side walls, a damper element provided in said casing, and means for pivotally securing said damper element to said cross member.

60 3. A fluid control device comprising, a substantially rectangular casing, said casing having top and side walls, a sealing member extending between said side walls in spaced relation to said top wall, a hook secured to said top wall adapting said casing for attachment to a tuyère block, a 65 cross member secured to said side walls, a damper element mounted in said casing, and means comprising one or more straps for pivotally securing said damper element to said cross member.

70 4. A fluid control device comprising, a substantially rectangular casing, said casing having

top and side walls, a sealing member extending between said side walls in spaced relation to said top wall, a hook secured to said top wall adapting said casing for attachment to a tuyère block, a 5 cross member secured to said side walls, a damper element provided in said casing, means for pivotally securing said damper element to said cross member, and means provided on said side walls for supporting said damper in open position.

5 In a device of the class described, the combination of a tuyère block, means provided on said tuyère block defining one or more inlet passages for draft air, a fluid control device operatively associated with each of said passages, each of said fluid control devices comprising a casing, 10 means provided on said casing for detachably securing the same to said tuyère block, and an automatically operable damper pivotally mounted in said casing and extending longitudinally thereof for controlling the flow of air to said 15 passages.

15 6. In a device of the class described, the combination of a tuyère block, means provided on said tuyère block defining an inlet passage for fluid, and a unitary damper mechanism detachably secured to said tuyère block for controlling the flow of fluid in said passage, said damper mechanism comprising a casing disposed longitudinally of said tuyère block and communicating with said inlet passage, a hook secured to said 20 casing and adapted to engage over the end of said tuyère block, and a damper pivotally mounted in said casing and extending longitudinally thereof.

25 7. In a device of the class described, the combination of a tuyère block, means provided on said tuyère block defining an inlet passage for draft air, a damper mechanism for controlling the flow of fluid in said passage, said mechanism comprising a casing adapted for attachment to said tuyère block, said casing extending longitudinally of said tuyère block and communicating with said inlet passage, a damper element mounted in said casing and extending longitudinally thereof, and longitudinally adjustable means for pivotally attaching said damper element to said casing.

30 8. In a device of the class described, the combination of a tuyère block, means provided on said tuyère block defining one or more inlet passages for draft air, a fluid control device mounted 40 on said tuyère block adjacent each of said passages for automatically controlling the flow of draft air thereto, each of said fluid control devices comprising a casing, means provided on said casing for detachably securing the same to said 45 tuyère block, and a damper element operable by differential pressure pivotally mounted in said casing and extending longitudinally in respect to the direction of air flow therethrough.

50 9. In a device of the class described, the combination of a tuyère block, means provided on said tuyère block defining one or more inlet passages for draft air thereto, each of said fluid control devices comprising a casing, means provided on said casing for detachably securing the same to said tuyère block, and a damper element operable by differential pressure pivotally mounted in 55 said casing and extending longitudinally in respect to the direction of air flow therethrough, and sealing means disposed at one end of said damper to prevent air leakage to said passage.
